[57] CLAIM

The ornamental design for a swivel hanger, as shown and described.

DESCRIPTION

FIG. 1 is an oblique view of one embodiment of the swivel hanger of the instant invention.

FIG. 2 is an elevation view of one side of the swivel hanger embodiment of the instant invention as shown in FIG. 1.

FIG. 3 is an elevation view of the opposite side of the swivel hanger embodiment of the instant invention as shown in FIG. 1.

FIG. 4 is a side elevation view of the swivel hanger embodiment of the instant invention taken from the left side of FIG. 1.

FIG. 5 is a side elevation view of the swivel hanger embodiment of the instant invention taken from the right side of FIG. 1.

FIG. 6 is a top view of the swivel hanger embodiment of the instant invention as shown in FIG. 1.

FIG. 7 is a bottom view of the swivel hanger embodiment of the instant invention as shown in FIG. 1.

FIG. 8 is an oblique view of another embodiment of the swivel hanger of the instant invention.

FIG. 9 is an elevation view of one side of the swivel hanger embodiment of the instant invention as shown in FIG. 8. The opposite side is the mirror image.

FIG. 10 is a side elevation view of the swivel hanger embodiment of the instant invention taken from the left side of FIG. 8.

FIG. 11 is a side elevation view of the swivel hanger embodiment of the instant invention taken from the right side of FIG. 8.

FIG. 12 is a top view of the swivel hanger embodiment of the instant invention as shown in FIG. 8; and,

FIG. 13 is a bottom view of the swivel hanger embodiment of the instant invention as shown in FIG. 8.
